UNITED STATES PATENT OFFICE

GEORGE J. FRANCIS, OF DURHAM, CONNECTICUT

CASH-BOX LATCH

Application filed July 17, 1925. Serial No. 44,266.

This invention relates to locks and latches and has particular reference to a latch device for use on cash boxes and the like.

The object of the invention is to provide

5 a latch device for use in connection with cash boxes and the like irrespective of or independent with respect to the lock mechanism thereon whereby the cover of the box may be held closed even though the box is unlocked, the advantage being that in case the box is lifted by the hand loop generally provided in the top there will be no danger of the top opening and the contents of the box being dropped out.

15 It is well known that cash boxes are ordinarily provided with a lock mechanism including a casing, a bolt operating therein, a supporting member within the cover and a pair or more of depending keeper 20 elements carried by the supporting element and cooperating with the lock bolt for positively securing the cover in closed position. However, boxes of this type are not ordinarily provided with any latch means which 25 will hold the cover positively closed while not locked and it is to make up for this deficiency that the present invention has been designed.

A more specific object of the invention is 30 to provide a latch device which is mounted directly upon the keeper support and which cooperated with the lock casing for the purpose of holding the box cover closed, simple means being provided operable from a point near the lock to effect release of the latch.

Another object of the invention is to provide 35 a lock mechanism in which the casing is so formed that the parts thereof may be readily placed together or disconnected if such is desired without a necessity for the employment of special tools for this purpose.

An additional object is the provision of 40 a device or construction of this character which will be simple and inexpensive, easy to install, positive in action, and a general improvement in the art.

With the above and other objects and advantages in view, the invention consists in 45 the details of construction and the arrange-

ment and combination of parts to be hereinafter more fully described and claimed, and illustrated in the accompanying drawings, in which:

Figure 1 is a front elevation of a cash box 55 with parts broken away, and in section, to illustrate the invention.

Figure 2 is a section on the line 2—2 of Figure 1.

Figure 3 is a plan view showing the latch 60 device mounted upon the keeper support.

Figure 4 is a front elevation of what is disclosed in Figure 3.

Figure 5 is a perspective view showing the 65 main portion of the lock casing.

Figure 6 is a detail perspective view of the front plate of the lock, and

Figure 7 is a detail cross section.

Referring more particularly to the drawings, the numerals 10 and 11 designate respectively portions of the body and cover of a cash box or the like. It is well known that boxes of this general type are equipped with locking means including a lock casing 12 secured within the body 10 of the box 70 and enclosing a bolt structure operated by means of a key insertible through the usual key hole 13. Details of the lock mechanism are not shown as they form no part of the present invention though it is of course 75 understood that whatever bolt structure is provided cooperates with a pair of depending notched keeper members 14 carried by an angle plate or bar 15 secured within the cover portion 11 of the box so that the box 80 may be positively locked when such is desired.

As stated above boxes of this type are not provided ordinarily with latch means for holding the cover closed without being 85 locked, and to remedy this lack I provide a latch mechanism which may very conveniently comprise an elongated leaf spring member 16 of angular formation having one end positively secured as by a rivet or the like 17 to the angle bar or plate 15 as clearly indicated in Figures 3 and 4. The free end of this spring member is stamped, punched or otherwise formed to provide an outstanding lip 18 formed in a downwardly ex- 90 95 100

tending portion 19 of the free end. To accommodate this latch device and to provide means cooperating therewith for holding the cover closed, the angle plate or bar 15 is formed with a slot 20 and the upper end of the casing 12 is formed with a similar slot 21 registering therewith, these slots being so located that the depending end portion 19 of the latch may enter them with the lip 18 engaging against the underside of the upper end of the lock casing as clearly shown in Figure 2.

In carrying out the second feature of the invention, namely, the manner of constructing the lock casing so as to facilitate assembling or disassembling thereof, it will be observed by referring to Figures 5 to 7 inclusive, that the lock casing generally indicated by the numeral 12 includes two sections 27 and 28, the former of which is of a rectangular box-like construction provided at its ends with laterally projecting apertured ears 29 provided for attachment to the box 10, and the latter of which is formed 25 as a plate complementary to the box-like structure. This section 27 includes a top portion 30 provided with the above described holes 21 and further provided with an opening 31 which receives the catch element or retaining element carried by the cover. Within this section 27 is the plate 32 of the lock device which carries the keeper 33. The essential feature is that the end portions of the section 27 are provided 35 with elongated slots 34 which receive correspondingly shaped lugs 35 on the ends of the plate 28 which carries the lock boss 36 which extends through the usual opening 37 in the front of the box.

40 Assuming that the entire lock structure has been removed from the box, it will be apparent that if the operator holds the sections 27 in one hand and grasps the lock boss 36 in the other hand he may, by pulling 45 in opposite directions on these elements, bow the plate 28 to a sufficient extent that the lugs 35 at the ends thereof may be withdrawn from the slots 34 in the ends of the casing section 27. In a similar or opposite manner it is apparent that assembling of 50 these parts may be equally easily accomplished.

For effecting release of the latch, I preferably provide a small plunger 22 slideable 55 through registering holes 23 and 24 in the front of the box cover and in the vertical flange of the angle plate or bar 15. The outer end of this plunger is equipped with a head or button 25 while the inner end is connected with the free end portion of the leaf spring, preferably by means of a reduced extension 26 passing through a suitable hole in the spring member and upset to maintain permanent connection.

60 Normally, the resilience of the spring 16

is such as to maintain it in a position where it will enter the slots 20 and 21 upon closing of the box cover, the outward extension or angularity of the lip 18 providing a beveled surface which will engage against an edge 70 of the slot 20 for springing the member 16 away from the side of the cover to permit the extension 19 to pass through the slots 20 and 21. Immediately after such passage the spring member 16 will return to its normal 75 position with the lip 18 engaging against the lower surface of the top portion or upper end of the slot casing 12. Obviously, when this is done, the cover will be held positively closed without requiring any manipulation whatever of the lock device ordinarily provided. To effect release so that the box cover may be opened, it is merely necessary that the operator press upon the head or button 25 so as to force the spring 80 member 16 inwardly and disengage the lip 18 from the lock casing, subsequently to which the cover may be swung open in the usual manner.

From the foregoing description and a 85 study of the drawings, it will be readily apparent that I have thus provided a very simple and inexpensive latch device which may be constructed as an attachment for application to already existing boxes or 90 which may be built into new ones as part of the original equipment. Attention is directed to the fact that the latch device is mounted directly upon the keeper carrying angle member and that it has an out-struck 95 element thereon cooperating with the lock casing itself, it being unnecessary to provide additional keeper means of any kind. It is believed that the construction, operation and advantages will be readily apparent to one 100 skilled in the art without further explanation.

While I have shown and described the preferred embodiment of the invention, it should be understood that I reserve the right 110 to make such changes in the form, construction, and arrangement of parts as will not depart from the spirit of the invention or the scope of the subjoined claim.

Having thus described the invention, I 115 claim:

In a cash box having a hinged flanged closure and having a key operated lock whose casing is fixed to one wall thereof and which casing has its top provided with 120 openings, one of which is of rectangular formation, a right angular plate having one of its flanges fixed to the inner face of the closure and its second flange designed to overlie and rest on the top of the lock casing 125 and the said last mentioned flange having depending notched keepers to be received through the first mentioned openings in the lock casing and which notched keepers are designed to be engaged by the bolt of the 130

lock, the said last mentioned flange having a rectangular opening therein to register with that of the lock casing, the fixed flange of the angle plate having secured thereto one end of an offset spring whose other end is formed with a depending portion designed to pass through the rectangular opening in the second flange of the angle plate and through the rectangular opening in the 10 top of the casing and to be urged against one of the longitudinal walls provided by these openings by the tension of the spring, said depending portion being formed with an angle lip to overlie and to contact with 15 the inner face of the top wall of the lock casing and a push element passing through the fixed flange of the plate and through the cover and fixed to the spring at the end thereof provided with the depending portion.

20 In testimony whereof I affix my signature.

GEORGE J. FRANCIS.
